UNITED STATES PATENT OFFICE

2,602,123

THERMALLY ACTUATED SWITCH

Chester I. Hall, Schenectady, and John L. Slonenger, Scotia, N. Y., assignors to General Electric Company, a corporation of New York

Application May 10, 1950, Serial No. 161,088

2 Claims. (Cl. 200—141)

1

This invention relates to electric switches of the thermally actuated type and more particularly to switches of this type which include therein a conducting liquid such as mercury.

In gas furnaces and the like there is need for safety apparatus to detect failure of the pilot flame to prevent possible explosive damage due to the presence of unignited fuel in the furnace in the event of such a failure. In general it is desirable to employ electrical switching devices, actuated by temperatures responsive to the presence or absence of the pilot flame, to actuate warning devices or to effect shut-off of the fuel supply through suitable valve devices. Switching devices employed for this purpose preferably have relatively rapid response and at the same time capacity to switch appreciable electrical loads. In addition, the switching elements are preferably hermetically sealed to prevent open sparking with accompanying danger of explosion. It is, of course, essential that switches employed as safety devices possess a high degree of reliability.

It is a general object of the present invention to provide a new and improved thermally actuated switch which is particularly useful as a safety switch in gas furnaces and the like, although not limited to such applications, and which includes the above-mentioned and other desirable features.

In accordance with the invention, a small portion of a conductive liquid, such as mercury, confined in a closed system is subjected to relatively high, or relatively low temperatures due to the presence or absence, respectively, of a flame or the like in the vicinity of the liquid. At temperatures above the vaporization temperature of the liquid, a portion of the exposed liquid is vaporized. The vapor pressure thus created forces the liquid into contact with a switching electrode, thereby forming a conductive path therebetween and effecting a switching operation. Upon cooling, the heated vapor is condensed to a liquid and the pressure of an inert gas, also confined in the closed system, forces the liquid out of contact with the switching electrode, thereby interrupting the conductive path therebetween and effecting a switching operation opposite in sense to the operation previously effected.

The invention will be better understood by reference to the following description taken in connection with the accompanying drawing, and the features of the invention believed to be novel will be pointed out in the appended claims. In the drawing Fig. 1 shows an embodiment of a thermally actuated switch constructed in accordance with the invention; Fig. 2 is a cross-section

2

taken along the line 2—2 of Fig. 1; Fig. 3 is a pressure-temperature characteristic graph of the liquid in the tube of the switch; and Fig. 4 is a schematic diagram of a thermostatic control apparatus including a device of the type shown in Figs. 1 and 2.

Referring now to Fig. 1, there is shown a thermally actuated switch 1, arranged to detect the presence or absence of a pilot flame 2 from a burner 3. Burner 3 is supplied with suitable fuel, such as gas, through a supply tube 4. For convenience, a body member 5 is provided which serves as the supporting structure for switch 1, burner 3 and tube 4. More particularly, an internal passageway 6 is provided in the lower portion 7 of body 5 for conducting gas from tube 4 to burner 3. Tube 4 is secured, as by brazing, to portion 7 at the lower end of passage 6 and burner 3 is secured in portion 7 at the upper end of passage 6. Burner 3 is shown as being screwed to portion 7 by tapered threads 8 to permit ease of replacement of burner 3. A suitable opening 9 is provided at the lower extremity of burner 3 to admit air for combustion. A plurality of openings 10 are provided at the upper extremity of burner 3 to permit escape of the combustible air-gas mixture to form flame 2.

A body member 11 is provided to form the main supporting structure for the elements of switch 1. Member 11 is secured to an upwardly extending portion 12 of body 5 by a pair of bolts 13 and nuts 14. As may be seen by reference to Fig. 2, body 11 is divided into two separate portions 11a and 11b along a surface 15, portions 11a and 11b being secured together by pairs of bolts 16 and nuts 17. Portions 11a and 11b may conveniently be formed of a molded material of a type suitable for the temperatures encountered in the vicinity of switch 1. A relatively small bulb 18, preferably formed of glass, is positioned in a cavity 19 in body 11. A capillary tube 20, preferably formed of an electrically conductive material such as metal, is secured in bulb 18 at the lower end thereof, the extremity 21 of tube 20 being positioned at substantially the longitudinal midpoint of bulb 18, as shown in Fig. 2. Tube 20 which is generally U-shaped, is positioned in a recessed portion 22 of body 11 so that the other extremity 23 of tube 20 is positioned at the upper portion of body 11. A second bulb 24, formed of a material suitable for use in the vicinity of flame 2, is secured to extremity 23 of tube 20. Bulb 24 may conveniently be in the form of a flattened tube, one of the flat surfaces thereof being exposed to flame 2.

An electrode 25 is secured in the upper extrem-

ity of bulb 18. Bulb 24 and tube 20 are completely filled with mercury 26 which extends into bulb 18 so that the level of the mercury 26 therein is between extremity 21 of tube 20 and the lower extremity 27 of electrode 25. The volume of bulb 18 above mercury 26 is charged with an inert gas 28, such as nitrogen, which may conveniently be at atmospheric pressure. The system of vessels comprising bulb 18, tube 20 and bulb 24 is sealed to prevent escape of gas therefrom. A window 29 is provided in body 11 to permit viewing the level of mercury 26 in bulb 18. A flexible lead 30 is connected between electrode 25 and a pair of electrically connected screws 31 of insulating terminal block 32 secured to body 11. Tube 20 serves as the other electrode of the switch through contact with mercury 26. A flexible lead 33 is connected between tube 20 and electrically connected screws 34 on terminal block 32. Screws 31 and 34 are provided as external connections of switch 1.

The operation of switch 1 is as follows. At relatively low temperatures mercury 26 is caused to fill tube 20 and bulb 24 by the pressure of gas 28. Under this condition, which exists when pilot flame 2 is not lighted, mercury 26 does not contact electrode 25 and switch 1 is open. When pilot flame 2 is lighted, bulb 24 is heated thereby to a relatively high temperature. Bulb 24 is constructed with a large surface area exposed to the flame so that heat from the flame is quickly transferred to the relatively small amount of mercury therein. The volume of mercury in bulb 24 is small compared to the volume of mercury in the relatively cool tube 20 and bulb 18 so that little heat is transferred to the mercury therein.

The mercury level in bulb 18 vs. mercury temperature in bulb 24 is shown in Fig. 3 by a curve. Initially, at relatively low temperatures, when liquid mercury is present in bulb 24, expansion of the liquid mercury occurs as the temperature thereof is increased. This expansion slightly raises the level of the mercury in bulb 18 as shown by leg 43 of the graph. At the vaporization temperature 44 of the mercury under the inert gas pressure in bulb 18, vaporization of some of the mercury in bulb 24 takes place causing a substantial increase in mercury level in bulb 18. Since the volume of the inert gas 28 is reduced as a result of the increased mercury level in bulb 18, the temperature of mercury in bulb 24 must be increased slightly to drive all of the liquid mercury out of bulb 24. After all the liquid mercury has been driven out of bulb 24, conditions of superheat exist in bulb 24 represented by leg 45 of the graph and relatively little increase in pressure accompanies further increase in heat of the vaporized mercury. This feature prevents excessive pressures in glass bulb 18.

Upon removal of flame 2, the same high ratio between exposure area and the volume of mercury in bulb 24 cools the mercury vapor, so that heat rapidly leaves the mercury causing it to condense again to liquid mercury. Upon condensation of the mercury, pressure of gas 28 in bulb 18 forces the mercury level down through tube 20, thereby breaking the contact with electrode 25, opening switch 1.

The construction shown is particularly adapted to obtaining a switch action which is relatively rapid, both in closing switch 1 due to heating bulb 24 and opening switch 1 due to cooling bulb 24. Since the mass of bulb 24 and liquid mercury 26 therein is relatively small, vaporization

occurs in a relatively short time after lighting of flame 2. It has been found that closing of switch 1 may be effected in two or three seconds following the lighting of flame 2.

While vaporization of mercury is described herein as occurring in a bulb 24 at the extremity of tube 20, it will be obvious that no special bulb need be provided and that if the extremity of tube 20 is sealed vaporization may equally occur in tube 20 itself. It is only necessary that the amount of mercury displaced due to vaporization be equal to the volume required to raise the level of mercury in bulb 18 to provide contact with electrode 25, with reasonable overtravel to secure reliable operation. Although in the embodiment described tube 20 is shown as being U-shaped, it will be obvious that such a configuration is not required and that tube 20 may project downwardly or horizontally from bulb 18 since positive transfer of mercury through tube 20 is effected in both directions.

A particular feature of the construction shown comprises extending tube 20 to substantially the longitudinal midpoint of bulb 18 and introducing mercury into the closed system until bulb 24 and tube 20 are filled and the mercury extends in bulb 18 substantially halfway between the end 21 of tube 20 and the end 27 of electrode 25. With this arrangement, extremity 21 of tube 20 is always covered by liquid mercury regardless of the position of switch 1 so that there is no tendency for gas 28 to enter capillary tube 20 and bulb 24 even if the switch should be inverted as might occur, for example, in shipment.

While the pressure of gas 28 at normal room temperatures may conveniently be atmospheric pressure, the operating temperature of switch 1 may be readily adjusted by varying the pressure of gas 28 when the system is initially charged. Thus if the pressure of gas 28 is increased the vaporization temperature of mercury 26 is likewise increased. It will be noted that due to the leveling off of pressure under superheating conditions, there is, for a particular initial gas pressure, a definite pressure limit to which the apparatus is subjected in operation and thus danger of failure due to bursting is minimized. A disadvantage of increasing the pressure of gas 28 above atmospheric pressure is that in case of opening of the sealed system due to breakage, for example, there is a tendency for mercury to be forced out of the system. The switch is a fail-safe device since opening of the switch occurs in the event of failure of flame 2, and when the bulb is broken the level of the mercury in bulb 18 falls also opening the switch. In addition to the above-mentioned features, the invention provides a switching apparatus having no moving mechanical parts and capable of switching a relatively large amount of electric power; furthermore switching takes place in a hermetically sealed system, thereby eliminating open sparking.

Attention is now directed to Fig. 4 in which there is shown a thermostatic control apparatus in which a switching device 1, of the general type described above and shown in Figs. 1 and 2, is actuated by an electrical heating element 35 in response to opening and closing of a thermostatic switch 36. Switch 1, as shown in Fig. 4, is intended to comprise the same elements as shown in Figs. 1 and 2. However, for convenience switch 1 is represented schematically in Fig. 4 and it will be understood that certain of the elements associated with the switch 1 are not shown.

therein. Heating element 35 is represented as a helix of resistance wire wound about bulb 24 and suitably insulated therefrom. Electrical energy for heater 35 is supplied from an electrical source 37 of alternating current, which is impressed on the primary winding 38 of a transformer 39. The secondary winding 40 of transformer 39 is connected in series relation with heater 35 and the contacts 41 of thermostat 36. Thermostat 36, which may be any of a number of conventional thermostatic devices, is represented in Fig. 4 as having a bimetallic element 42, the bending of which, in response to temperature changes, causes opening and closing of contacts 41.

If it is assumed that contacts 41 are caused to close in response to heating of element 42, electrical energy is supplied to heater 35 which, in turn, causes heating of bulb 24 and vaporization of the mercury therein. It will be obvious that the switching action of switch 1 is similar to the action previously described in connection with the arrangement of Figs. 1 and 2. Thus in the apparatus of Fig. 4 a relaying action is provided since actuation of contacts 41 by heating of element 42 causes actuation of switch 1. While actuation of switch 1 is shown as being caused by action of a thermostat 36, it will be obvious that other devices, such as a manual switch, may be employed to open and close the circuit of heater 35.

While we have shown and described certain preferred embodiments of our invention it will be understood that our invention may well take other forms and we, therefore, aim in the appended claims to cover all such changes and modifications as fall within the true spirit and scope of the invention.

What we claim as new and desire to secure by Letters Patent of the United States is:

1. A thermal switch comprising a frame, a vertical bulb of insulating material secured to said frame, an electrode sealed in the top of said bulb and extending into the interior thereof, an electrically conductive capillary tube sealed in the bottom of said bulb, the opposite end of said tube being sealed and of a heat conductive material and projecting from said bulb, a pair of terminals insulatingly secured to said frame and respectively electrically connected to said electrode and said tube, mercury entirely filling said tube at all times and filling said bulb to a level between said tube and said electrode, an inert gas filling the remainder of said bulb, means for heating the heat conductive end of said tube to

heat the mercury therein, said mercury being responsive to heating of said sealed end above a predetermined temperature to vaporize therein and cause mercury from said tube to rise in said bulb and complete an electric connection between said terminals, said mercury being also responsive to cooling of said sealed end below said predetermined temperature to condense therein to allow the pressure of said inert gas to force mercury into said tube to break the connection, said sealed end being formed to provide an increased surface for rapid transfer of heat between the wall of said tube and said mercury.

2. A thermally actuated switch comprising a frame, a vertical bulb of insulating material secured to said frame, a pair of electrodes, one of said electrodes being sealed in the upper end of said bulb and extending into the interior thereof, an electrically conductive capillary tube having the open end thereof extending into said bulb to substantially the midpoint thereof to serve as the other of said electrodes, the opposite end of said tube being sealed and of a heat conductive material and extending above said bulb, a quantity of mercury entirely filling said tube and filling said bulb to a predetermined level substantially midway between said electrodes, an inert gas filling the remainder of said bulb, a pair of terminals secured to and insulated from said frame and respectively electrically connected to said electrode and said tube, means for heating the heat conductive end of said tube to heat the mercury therein, said mercury being responsive to heating of said sealed end to vaporize and thereby force the mercury from said tube to flow into said bulb to raise the level of said mercury therein above the end of said electrode and compress said gas, thereby completing an electrical connection between said terminals, said mercury being also responsive to cooling of said sealed end to condense therein and allow the pressure of said inert gas to force mercury back into said tube thereby breaking said connection.
